TION OF MICHIGAN

MOLDING APPARATUS

Application filed August 17, 1928. Serial No. 300,286.

The invention relates to molding apparatus and has been developed in casting articles from metals, such as aluminum or its alloys, having a high crystallization shrinkage and a low fusing point. One of the objects of the invention is to provide a form of molding apparatus which may be quickly and readily operated and which has a core insertable into the mold cavity and adapted to support the casting while the mold sections are being separated. Another object is to provide a simple construction for guiding and supporting the core. A further object is to provide an improved means for clamping the mold sections together. With these as well as other objects in view, the invention resides in the novel features of construction and combinations and arrangements of parts as more fully hereinafter set forth.

In the drawings:—

Figure 1 is a plan view of a molding apparatus embodying our invention;
Figure 2 is an end view thereof;
Figure 3 is a cross section on the line 3—3 of Figure 1.

In the present instance the molding apparatus embodying our invention is designed for use in casting articles, such as a spray gun, and has the base 1 and the permanent metal mold sections 2 and 3, which are adapted to swing horizontally upon the base about the vertical pin 4 secured to the base and engaging one end of the mold sections. The adjacent faces of these mold sections are formed with recesses which register when the mold sections are together to form the mold cavity 5 and the gate 6. This mold cavity is located between the tops and bottoms of the mold sections and terminates near the free ends thereof. 7 is a horizontally movable permanent metal core, which is adapted to be inserted longitudinally into the mold cavity to make a portion of the casting hollow. This core is guided and supported by the cradle 8, which is fixedly secured upon the base 1 adjacent to the free ends of the mold sections when in closed casting position. The core has the shoulder 9, which is spaced from the cradle 8 suffi-

ciently to permit the insertion of a pry to remove the core from the mold cavity. The core also has the handle 10 principally for inserting the core into the cavity.

To clamp the mold sections 2 and 3 in their closed casting position, we have provided the metal clamping yoke 11 having the legs 12 and 13 with the leg 12 pivotally connected to the outer side of the mold section 2 by the horizontally extending pin 14. This yoke is adapted to swing through a vertical path and to embrace the reduced portions 15 at the free ends of the mold sections. 16 is a cam member having the head 17 and the handle 18 with the head 17 pivotally connected to the leg 13 of the yoke by the horizontally extending pin 19. The head is positioned relative to the mold section 3 so that its cammed or eccentric face is engageable with this mold section to tightly clamp the same against the mold section 2. The top 20 of the clamping yoke is of T cross section, it having the lateral flanges 21 at its lower edge and extending above the legs 12 and 13, which are bifurcated to embrace the bracket 75 22 fixedly secured to the outer side of the mold section 2 and the head 17 of the cam member.

From the above description, it will be readily seen that we have provided a simple construction of molding apparatus which may be readily and quickly operated and which is so arranged that the core is adapted to support the casting while separating the mold sections, it being understood that before these mold sections are separated the core is first partially withdrawn. It will also be seen that we have provided a simple construction of core guide and support which is located beyond the mold sections and an effective arrangement for clamping the mold sections together in their closed or casting position.

What we claim as our invention is:

1. In a molding apparatus, the combination with a base, of mold sections upon said base adapted to cooperate to form a mold cavity, and means for clamping said sections together, including a yoke pivotally mounted upon one of said sections and movable

through a path transverse to said base to embrace said sections, and means upon said yoke and engageable with one of said sections for forcing one toward another.

5 2. In a molding apparatus, the combination with a base, of means for forming a mold cavity, including a pair of horizontally movable mold sections upon said base having reduced portions, and means for clamping said sections together, including a yoke pivotally mounted upon one of said sections and adapted to swing through a vertical path and to embrace the reduced portions of said sections, and a cam member upon the free end 10 of said yoke and engageable with the adjacent section for forcing the same toward the other section.

20 3. In a molding apparatus the combination with a base, of a pair of pivotal mold sections upon said base adapted to cooperate to form a mold cavity terminating near the free ends thereof, a core insertable into the mold cavity, a cradle upon said base adjacent the free ends of said sections for guiding said 25 core, a yoke pivotally connected to one of said sections adjacent its free end and adapted to swing through a vertical path to embrace said sections, and a cam member upon the free end of said yoke and engageable with the adjacent section to force the same toward 30 the other section.

35 4. In a molding apparatus, the combination with a base, of means for forming a mold cavity comprising a pair of pivotal mold sections upon said base having reduced free 40 end portions, a core insertable into the mold cavity, a cradle upon said base adjacent the reduced portions of said sections for supporting and guiding said core, and means engageable with the reduced portions of said sections for forcing the sections toward each other.

45 5. In a molding apparatus, the combination with a base, of means for forming a mold cavity comprising a pair of pivotal mold sections upon said base having reduced free end portions, a core insertable into the mold cavity, a cradle upon said base adjacent the reduced portions of said sections for supporting and guiding said core, means engageable with the reduced portions of said sections for forcing the sections toward each other, including a yoke pivoted upon one of said sections and adapted to swing through 55 a vertical path to embrace the reduced portions of said sections, and a cam member upon the free end of said yoke and engageable with the adjacent section for forcing the same toward the other section.

60 6. In a molding apparatus, the combination with a base, of means for forming a mold cavity comprising a pair of pivotal mold sections upon said base, a core insertable into the mold cavity, a member upon said base 65 adjacent the free ends of said sections for

guiding said core, and means engageable with said sections for forcing the same toward each other.

7. In a molding apparatus, the combination with a base, of means for forming a mold cavity comprising a pair of pivotal mold sections upon said base, a core insertable into the mold cavity, a member upon said base adjacent the free ends of said sections for guiding said core, and means for clamping said sections together including a member pivotally mounted upon one of said sections and movable through a path transverse to said base to embrace said sections.

In testimony whereof we affix our signatures.

ARTHUR T. BATEMAN.
ANDREW IRVINE.
